FISHING POLE HOLDER

John P. Freed, Rte. 4, Box 528,
Hot Springs, Ark. 71901

Filed Sept. 24, 1973, Ser. No. 400,150

Term of patent 14 years

Int. Cl. D22—05

U.S. Cl. D22—13

FIG. 1 is a perspective view of a fishing pole holder, showing my new design.

FIG. 2 is a perspective view thereof with the spike portion in stored position.

FIG. 3 is a side elevational view thereof.

FIG. 4 is a top plan view of the configuration of FIG. 2.

FIG. 5 is a view as taken from below FIG. 3.

I claim:

The ornamental design for a fishing pole holder, substantially as shown.
